UNITED STATES PATENT OFFICE.

CLARK S. COMSTOCK, OF EAST ORANGE, NEW JERSEY.

BUCKLE.

No. 904,048.

Specification of Letters Patent.

Patented Nov. 17, 1908.

Application filed January 29, 1908. Serial No. 413,148.

To all whom it may concern:

Be it known that I, CLARK S. COMSTOCK, a citizen of the United States, and a resident of East Orange, in the county of Essex and 5 State of New Jersey, have made and invented certain new and useful Improvements in Buckles, of which the following is a specification.

My invention relates to an improvement 10 in buckles, and more particularly to a device of this kind or character which is devised to be used with suspenders, shoulder straps attached to overalls, or similar articles, the object being to so construct the 15 buckle that the strap or suspender will be held flatly and firmly in position with respect thereto, whereby any tendency of the strap or suspender to bulge outwardly from the buckle and become accidentally detached 20 from the tongues or prongs thereof, is prevented.

Another object of my invention is to provide a device which is simple in its construction, and therefore cheap to manufacture, 25 and which will be strong and efficient in use.

With these and other ends in view, my invention consists in certain novel features of construction, as will be hereinafter fully described and pointed out in the claim.

30 In the accompanying drawings, Figure 1 is a view in elevation of my improved buckle attached to the suspender or strap. Fig. 2 is a sectional view taken on the line 2—2 of Fig. 1. Fig. 3 is a view in elevation of the 35 buckle detached from the suspender or strap.

Referring to Figs. 1, 2 and 3 of the drawings, the buckle is shown as consisting of two parts, the upper portion or frame A and the lower or body portion B, each of 40 which is constructed from a single piece of wire. The frame A is of the usual form, being bent to form the loop g, and having its ends bent to form eyes or sockets a for supporting the body portion of the buckle in 45 the well known manner. The lower or body portion B is preferably formed by bending the wire upward to form the vertical sides b, b, and at intermediate points thereof, the wire is bent inwardly and then backwardly 50 upon itself forming the tongues or retaining means c, c, for preventing the strap or suspender from bulging outwardly from the buckle and becoming accidentally disengaged from the tongues thereof, and also 55 forming the upper and lower loops d and e through which the suspender or strap passes

as hereinafter described. The ends of the wire forming the body portion B are bent to form the tongues f, f, which co-act with the frame A in the usual manner. The portions of the vertical sides b lying above and below the retaining means or tongues c, are preferably bent slightly backwardly, as shown in Fig. 2, whereby the bar a¹ of the frame A and the retaining means c will lie 65 in substantially the same vertical plane, thereby tending to keep the suspender or strap flat.

In practice, one end of the suspender or strap C is secured in any suitable manner 70 to the bar b¹ of the body portion B and the other end, after passing through a suitable button-loop D, or other suitable device, passes through the lower loop e, from the front side of the buckle, then under the retaining 75 means c, and through the upper loop d, after which it is secured or attached to the tongues f in the usual way, passing through the loop g in the frame A.

It will be seen that I have devised a buckle 80 which is simple in construction, and consequently cheap to manufacture, which will be efficient in use, and which is provided with means for holding the strap or suspender to which it is attached flat against 85 the same, thereby preventing the strap from bulging outwardly and becoming detached from the tongues of the buckle.

Having fully described my invention, what I claim as new and desire to secure 90 by Letters Patent, is:—

The buckle hereinbefore described and comprising the frame A and body B, the frame A being made of a single piece of wire and bent to form a cross bar, the free 95 ends of which are formed into sockets, the said body being also formed of a single piece of wire, the free ends of which pass through said sockets and are formed into tongues engaging with said frame, the sides 100 of the body being bent inwardly to within a short distance of each other forming transverse retaining means, substantially as described.

Signed at New York, borough of Manhattan, in the county of New York, and State of New York, this 28th day of January, A. D. 1908.

CLARK S. COMSTOCK.
